(57) **CLAIM**

The ornamental design for a bottle without cap, substantially as shown and described.

DESCRIPTION

FIG. 1 is a top, front perspective view of a bottle showing my new design;

FIG. 2 is a front elevational view hereof;

FIG. 3 is a right side elevational view thereof;

FIG. 4 is a rear elevational view thereof;

FIG. 5 is a left side elevational view thereof; and,

FIG. 6 is a top plan view thereof.

The bottom view of the bottle without cap forms no part of the claimed design.
